ORTHOPEDIC ARM SUPPORT

Elmer Arluck, New York, N.Y., and Myron S. Jenner,
Bethel, Vt., assignors to Thermo-Mold Medical Prod-
ucts, Inc., New York, N.Y.

Filed July 30, 1974, Ser. No. 493,128

Term of patent 14 years

Int. Cl. D24—04

U.S. Cl. D83—1 J

FIG.1

FIG.2

FIG.3

FIG.4

FIG. 5

FIG. 6

FIG. 7

FIG. 1 is a perspective view of an orthopedic arm support of the present invention;

FIG. 2 is a perspective view thereof from the opposite side;

FIG. 3 is a bottom perspective view thereof;

FIG. 4 is a side view thereof;

FIG. 5 is a top perspective view thereof;

FIG. 6 is a top perspective view thereof taken from a different viewing angle than FIG. 5; and

FIG. 7 is a front view thereof.

We claim:

The ornamental design for an orthopedic arm support, as shown.
